[57] ABSTRACT

A combined radiator cap and heater assembly wherein the radiator cap comprises a top plate and a bottom plate separated by a resilient means, such as a spring which normally keeps the bottom plate biased away from the top plate. Power carrying electrical conductors pass through a ferrule in the top plate into a tubular means connected to the top plate. The tubular means has a flange thereon for movably securing the bottom plate thereto in a manner which enables the bottom plate to move longitudinally along said tubular means. A tube attached to the tubular means holds and extends a heater into the water in the radiator. The conductors pass through the tube to the heater.

FIG. 2

FIG. 1

FIG. 3

COMBINED RADIATOR CAP AND HEATER ASSEMBLY

My invention relates to heating devices, and more particularly to electric heaters, adaptable for combination with the radiator cap on automotive vehicles, or the like.

The automobile radiator fluid is normally heated by the heat generated in the internal combustion engine. There are many times, such as on cold days when it is desirable to speed up the heating process. Accordingly, the prime object of my invention, is to provide a means of suspending an electrically actuated resistance coil from the radiator cap. The coil is employed for heating the water in the radiator that forms a part of an internal combustion engine assembly.

A further object is to provide a device, designed to let the steam escape, if the water in the radiator becomes overheated.

Another object of my invention is to provide a device of the character described, that is designed to be energized by the battery or other direct current, such as, the automobile alternator or generator, although commercial current is preferred.

Still another object of the invention is to make the heater coils combinable with the radiator caps of conventional design.

The device is simple in construction, and requires no special mechanical skill for its manipulation.

A preferred embodiment of the invention comprises a combined radiator cap and heater assembly wherein the radiator cap is made up of a top plate secured to the upper opening around the radiator spout. A ferrule in the top plate enables passage therethrough of electrical conductors. Attached to the top plate is a tubular member which receives the electrical conductors for passage therethrough. The bottom of the tubular member is flanged. A bottom plate is movably secured to the tubular member by the flange and is biased away from the top plate by a spring. The bottom plate normally seals the spout of the radiator. A tube is attached to the tubular member and holds an electrical heating device in the radiator water. The conductors extend through the tube to the heating device.

Other and further objects of my invention will become more apparent as the description proceeds when taken in conjunction with the drawings, in which:

FIG. 1 is a perspective view of the entire assembled device constituting my invention;

FIG. 2 is a vertical cross-sectional view of the assembled device in a closed, or sealed, position; and

FIG. 3 is a similar view as shown in FIG. 2 in a released or open position to enable the steam from the over-heated radiator to be released.

Similar character of references indicate corresponding parts and features throughout the several views. Referring now to the same, the character 10 indicates a conventional radiator cap which may be of standard design, shown equipped with downwardly extending, angular retaining hooks 11, and outwardly extending ear members 12 (see FIG. 1). The cap 10 is designed for selective engagement with the radiator spout 13, shown in phantom in FIGS. 2 and 3.

The cap 10 is further provided with a centrally disposed ferrule 14, supporting a plate 15. In addition, a tubular member 16 is attached to the bottom of the ferrule 14 in any practical or efficient well-known manner.

The tubular member 16 has an outwardly extending flange 17 at the bottom thereof. The flange 17 engages a sealing plate 18. The plate 18 is equipped with a washer 19, which may be constructed of rubber or the like, that contacts a ridge 20, forming a part of the spout 13.

A compression spring 21 is disposed around the ferrule 14 between the bottom of the plate 15 and the upper surface of the plate 18. The spring is designed to keep the washer sealing in seal engagement with the ridge 20 under normal conditions.

As insulated wire of standard type shown as 22, passes through the ferrule 14, the tubular member 16 and a tube 23. The tube 23 engages the member 16 at 24. The tube 23 may be of any desired length to be submerged in the liquid, or water within the radiator, (not shown). The tube 23 supports a resistance coil 25, which may be of any conventional design, and employed to heat the water or liquid within the radiators. When the water in the radiator becomes overheated, the plate 18 is raised as shown at 2 in FIG. 3, against the pressure of the spring 21, to permit the steam or the like to escape from the radiator to return the pressure to normal without damaging the radiator.

From the above description it will be become apparent that the device is designed to perform the function for which it is intended. It may be energized either by a battery or by the alternator. Although I have shown a specific construction and arrangement of the parts and features constituting my invention, I am fully cognizant of the fact that many changes may be made without affecting the operativeness of the device, and I reserve the rights to make such changes, without departing from the spirit of my invention or the scope of the appended claims.

Having thus described my invention, what I claim and desire to secure by Letters Patent in the United States, is:

1. A heating device for automotive radiators, said radiators having radiator cap means, such heating device comprising an electrical heating element, said electrical heating element combined with and supported from said cap means, said radiator cap means comprising a top plate for attaching to the rim of the radiator opening, a bottom sealing plate resiliently biased away from said top plate, tubular means attached to said top plate and extending downwardly, said bottom sealing plate being slidably supported by said tubular means for movement longitudinally thereto, tube means attached to the bottom of said tubular means and extending downwardly therefrom, said heating element being affixed in said tube means, and conductor means extending through said top plate and said tubular means into said tube means to said heating element whereby said heating element extends into the water in the radiator

2. The heating device of claim 1 wherein said top plate comprises ferrule means at the top thereof enabling said insulated conductor means to extend from above said top plate to said heating element, and wherein said tube means is threadingly engaged to the bottom of said tubular means.

3. A heating device for automotive radiators, said heating device comprising an electrical heating element, radiator cap means, tube means for attaching said heating element in dependent fashion from said radiator cap means, said heating element being affixed to said tube means which is sufficiently long to extend into the water in the radiator, ferrule means at the top of said radiator cap means, 10 and means for energizing said heating element extending through said radiator cap and comprising insulated wire means coming through said ferrule means, said radiator cap comprising a top plate attached to 15 and surrounding said ferrule means, a tubular member attached to said top plate, said tube means being attached to the bottom of said tubular member with said insulated wire means running through said tubular member and said tube 20 means to said heating element,

a bottom sealing plate slidably secured to the lower end of said tubular member for movement longitudinally thereof, said tubular member having flange means at the bottom thereof for limiting the movement of said bottom sealing plate, and means for biasing said bottom sealing plate away from said top plate to sealingly engage the throat of the spout of the radiator.

4. The heating device of claim 3 wherein said means for biasing said bottom sealing plate comprises compression spring means mounted around said tubular member and extending from said top plate to said sealing plate, and

said compression spring being sufficiently resilient to compress and unseal said radiator at a predetermined pressure as a safety means for protecting against overheating said radiator.

5. The heating device of claim 4 wherein said heating element comprises a heating coil.

UNITED STATES PATENT OFFICE
CERTIFICATE OF CORRECTION

Patent No. 3,824,370 Dated July 16, 1974

Inventor(s) Joseph A Kucera

It is certified that error appears in the above-identified patent and that said Letters Patent are hereby corrected as shown below:

Col. 1, line 16 Before "a" (first occurrence)

change "provided" to -- provide --

Col. 2, line 5 After "that" change "cotacts"

to -- contacts --

line 10   After "washer" insert "19 in" and

before "engagement" omit "seali"

Signed and sealed this 24th day of December 1974.

(SEAL)
